[57] CLAIM

The ornamental design for a picture frame or the like, as shown and described.

DESCRIPTION

FIG. 1 is a front elevational view of a picture frame or the like showing my new design, the verso thereof being substantially plain and unornamented;
 FIG. 2 is a left side elevational view thereof;
 FIG. 3 is a right side elevational view thereof;
 FIG. 4 is a top plan view thereof; and
 FIG. 5 is a bottom plan view thereof.
